CLAIM

The ornamental design for a packaging device, as shown and described.

DESCRIPTION

FIG. 1 is a front, left, top perspective view of a packaging device showing our new design in a first configuration; FIG. 2 is rear, right, bottom perspective view thereof; FIG. 3 is a front view thereof; FIG. 4 is a rear view thereof; FIG. 5 is a top view thereof; FIG. 6 is a bottom view thereof; FIG. 7 is a left side view thereof, shown in enlarged scale; FIG. 8 is a right side view thereof, shown in enlarged scale; FIG. 9 is a front, left, top perspective view of the packaging device in a second configuration; FIG. 10 is front, left, bottom perspective view thereof; FIG. 11 is a front view thereof; FIG. 12 is a rear view thereof; FIG. 13 is a top view thereof; FIG. 14 is a bottom view thereof; FIG. 15 is a right side view thereof, shown in enlarged scale; FIG. 16 is a left side view thereof, shown in enlarged scale; FIG. 17 is a front, left, top perspective view of the packaging device in a second configuration, shown separately for completeness of illustration; FIG. 18 is front, left, bottom perspective view thereof; FIG. 19 is a front view thereof; FIG. 20 is a rear view thereof; FIG. 21 is a top view thereof; FIG. 22 is a bottom view thereof; FIG. 23 is a right side view thereof, shown in enlarged scale; FIG. 24 is a left side view thereof, shown in enlarged scale; FIG. 25 is a front, left, top perspective view of the packaging device in a third configuration; FIG. 26 is rear, right, bottom perspective view thereof; FIG. 27 is a front view thereof; FIG. 28 is a rear view thereof; FIG. 29 is a top view thereof; FIG. 30 is a bottom view thereof;

(Continued)

FIG. 31 is a left side view thereof, shown in enlarged scale;
 FIG. 32 is a right side view thereof, shown in enlarged scale;
 FIG. 33 is a front, left, top perspective view of a packaging device in a fourth configuration;
 FIG. 34 is rear, right, bottom perspective view thereof;
 FIG. 35 is a front view thereof;
 FIG. 36 is a rear view thereof;
 FIG. 37 is a top view thereof;
 FIG. 38 is a bottom view thereof;
 FIG. 39 is a left side view thereof, shown in enlarged scale; and,
 FIG. 40 is a right side view thereof, shown in enlarged scale.
